UNITED STATES PATENT OFFICE.

ARTHUR ERNEST JERRAM AND JOSEPH GOULDBOURN, OF LEICESTER, ENGLAND, AS-SIGNORS TO UNITED SHOE MACHINERY CORPORATION, OF PATERSON, NEW JERSEY, A CORPORATION OF NEW JERSEY.

MACHINE FOR WORKING UPPERS OVER LASTS.

Application filed May 12, 1920. Serial No. 380,874.

To all whom it may concern:

Be it known that we, ARTHUR E. JERRAM and JOSEPH GOULDBOURN, subjects of the King of England, and residents of Leicester, Leicestershire, England, have invented certain Improvements in Machines for Working Uppers Over Lasts, of which the following description, in connection with the accompanying drawings, is a specification, like reference characters on the drawings indicating like parts in the several figures.

This invention relates to machines for working uppers over lasts and is herein illustrated in its application to a machine for pulling over uppers and for fastening them in pulled-over position, although in many of its aspects the invention is not limited to pulling-over machines.

Among its important features, the invention provides novel means for presenting a fastener for use in an upper fastening operation. As applied to a construction having a fastener carrier mounted for movement from an initial retracted position toward fastener inserting position and for additional fastener transferring movement, the invention in its illustrative embodiment provides means for imparting to the carrier such fastener transferring movement while it is in its retracted position. In the construction shown each fastener inserting device is provided with a fastener carrier which moves with it toward and from fastener inserting position and is additionally movable into position to receive a fastener at a point of delivery and into position to present the fastener in the path of movement of the fastener driver while the fastener inserting device is in its retracted position. In the illustrative construction such presenting movement is imparted to the fastener carrier through connections which are broken by the movement of the fastener inserting device toward fastener inserting position, and the invention further provides means for locking the carrier in fastener presenting position when the connections are broken, the locking means in the construction shown acting automatically to lock the carrier upon its movement toward fastener inserting position and to unlock it upon its return movement. Further features are to be recog-

nized in a novel organization for controlling or effecting presentation of fasteners to a plurality of fastener inserting devices arranged to operate in different locations on a shoe, as for example in a well-known type of pulling-over machine, and in means for imparting to a fastener carrier its fastener transferring or presenting movement at a time in the cycle substantially later than the time of fastener delivery. In the illustrative machine movement into fastener receiving position is imparted to the fastener carriers in the first, or upper pulling, stage of the cycle in time to receive fasteners delivered in that stage, and the carriers are moved to present the fasteners to the drivers only upon a subsequent starting of the machine. Ample time is thus afforded for delivery of the fasteners and to permit them to come to rest in the carriers before they are transferred. The invention is herein shown as applied to a pulling-over machine of the type illustrated in Letters Patent No. 1,426,389 granted on Aug. 22, 1922, upon a joint application of the present applicants and Fred Ricks, having means for pulling over the upper of a shoe positioned bottom downward and means for presenting and driving fasteners point upward, and it is one object of the invention, among others, to provide improvements in the construction shown in said Letters Patent.

A further feature of the invention consists in novel means for delivering fasteners pneumatically to upper fastening means, the construction shown comprising means for producing a blast of air to effect fastener delivery in the first stage of the cycle, in which, as above set forth, the fastener carriers are moved to fastener receiving position. A feature is also to be recognized in novel means for producing a blast of air to effect fastener delivery, the construction shown comprising an air pump having a piston and a piston rod automatically disconnected in the suction stroke of the piston to release the piston to the action of a spring which effects its compression stroke.

The invention also provides a novel and improved construction of controlling means, the machine shown having a simple and effective construction and arrangement of

starting and stopping mechanism designed particularly for use in an organization in which the operating connections comprise different shafts disposed in angular relation to each other. Important advantages of the novel controlling mechanism are to be recognized in the application of the invention to a machine of the type illustrated in the prior patent above mentioned comprising an upwardly extending cam shaft connected to a substantially horizontal driving shaft. Included also in the illustrative machine, as a further novel feature, is means enabling the operator in his working position in front of the machine to release the brake without setting the clutch, thus permitting the machine to be turned manually through more or less of its operating cycle. In order to permit the operator to view readily the different operating instrumentalities as the machine is turned through its cycle manually, the invention also provides means which may be manipulated to turn the machine while the operator is in his normal working position in front of the machine, such means in the illustrative construction comprising a hand wheel mounted at the side of the machine and connected to the upwardly extending cam shaft. Combined with the means at the front of the machine for use in releasing the brake without setting the clutch, this arrangement for operating the machine manually permits a shift from power operation to manual movement of the parts, or vice versa, while the operator is in his normal working position.

Still another feature of the invention consists in a novel organization whereby a substantial portion of the operating mechanism of a shoe machine may be moved from its normal position into a different position in order, for example, to facilitate adjustments or repairs. In the construction shown the shoe rest, the upper pulling and fastening instrumentalities, and the upwardly extending cam shaft are mounted on a support which may be swung into position to present the cam shaft substantially horizontally, thus affording the operator convenient access to the interior of the machine while permitting a substantial portion of the structure to be normally inclosed in a casing for safety and for the purpose of excluding dirt from the interior of the machine. It is also a novel and advantageous characteristic of the construction shown that the means provided for turning the machine manually is operative in either position of the movable support.

Since the invention, as above stated, is herein shown as embodied in the type of machine shown and described in said prior patent and described more fully as to many of its characteristic features in numerous

prior United States Letters Patent including, for example, Patent No. 1,029,387, granted on June 11, 1912, upon an application of R. F. McFeely, the general organization of the machine, in so far as it is not modified for purposes of the present invention, will be described only briefly, and for a more complete understanding of the details of the construction reference may be made to said prior patents.

In the drawings:

Fig. 1 is a view in side elevation of a machine in which the invention is embodied, with parts broken away and in section to illustrate the interior construction;

Fig. 2 is a view in side elevation of parts of the machine shown in Fig. 1, illustrating a different position into which a portion of the machine may be moved for purposes of adjustment or repair;

Fig. 3 is a view substantially in plan showing, detached, portions of the machine which have to do with the overlaying and the fastening of the upper;

Fig. 4 is an end view of one of the tack carriers and associated parts;

Fig. 5 is a section on the line 5—5 of Fig. 6, and

Fig. 6 is an inverted plan view of a portion of one of the tack carriers.

Similarly to the machine shown and described in the prior patent first above mentioned, the machine herein shown is provided with a sole rest 2 and a heel rest 4 which position the last and the shoe bottom downward with the toe end of the shoe pointing upwardly and away from the operator to present the top of the forepart in full view of the operator as he stands in his normal working position. The shoe as thus mounted is substantially over the upper end of a substantially upright cam shaft 6 which carries the cams whereby movements are imparted to the different operating instrumentalities. For pulling the upper the machine is provided with a toe gripper 8 and with opposite side grippers one of which is seen at 10 in Fig. 1, the toe gripper and the side grippers being connected respectively to levers 12 and 14 which may be conveniently termed "updraw" levers. Upper pulling movement is imparted to the lever 12 by a cam 16 on the cam shaft 6 through a cam slide 18 and a yielding spring connection 20, and similar movement is imparted to the side updraw levers by a cam 22 through a cam slide 24 and yielding spring connections 26. It will be understood that, under the control of mechanism to be hereinafter described, upper pulling movement is imparted to the grippers through a partial rotation of the cam shaft, whereupon the machine comes automatically to rest with the upper held under tension to permit such adjustment of the tension and

of the lines of the upper on the last as the operator may observe to be necessary. Upon a subsequent starting of the machine opposite side clamp arms 28 are swung inwardly into supporting and clamping engagement with the shoe, and either immediately, or following a second stop in the operation of the machine, operative movements are imparted to the means whereby 5 the margin of the upper is overlaid and fastened on the bottom of the last. The overlaying and fastening means comprises a toe tacker arm 30 and side tacker arms 32 which are mounted for swinging movement 10 toward and from the shoe under the control of mechanism including a slide bar 34, these arms being severally provided with fastener inserting devices comprising driver bars 36 and tack drivers 37. It will be understood that by the inward movement of the arms 30 and 32 the margin of the upper is wiped inwardly over the bottom face of the sole or insole and the grippers are tripped to release the upper, and that at the 15 end of such inward movement of the arms the driver bars 36 are operated to drive the tacks, whereupon the arms 30 and 32 and other parts of the machine are returned to starting position, as more fully illustrated 20 and described in said prior patents.

Similarly also to the machine shown in said patents, the machine herein shown is provided with tack supplying means comprising a rotatable tack pot 38 and a tack separator indicated generally at 40 in Fig. 1, these parts receiving operative movement from an eccentric 42 on the cam shaft 6 through a link 44 connected to one arm of a bell-crank lever 46 the other arm of which 25 is connected to a vertical rod 48 which through rack and pinion mechanism serves to oscillate the tack pot. It will be understood that in operation, as in prior machines of the general type illustrated, downward movement is imparted to the rod 48 in the first stage of the cycle and that the rod receives its return upward movement in the final stage of the cycle following a subsequent starting of the machine.

From the tack separator 40 the tacks are conducted to the track driving mechanisms by means including readily detachable tack tubes 50 which, as in the construction shown in the first mentioned patent, extend upwardly from the separator and then downwardly to cause the tacks to be inverted and delivered point upward. The number of the tack tubes 50 corresponds to the number of tacks to be driven at each operation, the machine shown being adapted to drive a single tack at the end of the toe and two tacks at each side of the forepart. For lifting the several tacks from the separator and forcing them into and through the tubes 55 the machine is provided with pneumatic

means which in the present construction comprises a stationary pump cylinder 52 mounted on the column 41 which supports the tack separator, and a piston 54 mounted within the cylinder and normally held in its innermost position by a spring 56. The cylinder 52 is connected by means of a conduit 58 with openings whereby compressed air is directed upwardly against the several tacks, as will be understood by reference to the prior patent. Within the cylinder 52 is a piston rod 60 which is connected at its outer end to a lever 62 fulcrumed at 64 on the column 41 and having a pin and slot connection at 66 with the vertically movable rod 48. At its inner end the piston rod 60 is provided with a lug 68 to hook over a pin 70 in the piston 54, as indicated in Fig. 1, the rod being held normally in the position there indicated by means of a leaf spring 72 between one side of the rod and a part 74 on the piston. When downward movement is imparted to the rod 48 in the first stage of the cycle the lever 62 is swung toward the left (Fig. 1) and through the rod 60 pulls the piston outwardly against the resistance of the spring 56, air being admitted to the interior of the cylinder through a suitable check valve not herein shown. Toward the end of the operative movement of the lever 62 a cam shaped lug 76 on the piston rod engages an adjustable screw 78 and lateral movement is thereby imparted to the rod against the resistance of the spring 72 in such manner as to disconnect its lug 68 from the pin 70, whereupon the spring 56 acts to impel the piston into the cylinder and thereby to force a blast of air against the several tacks in line with the tack tubes 50 to blow the tacks into and through the tubes. When the rod 48 receives its return upward movement in the final stage of the cycle the piston rod 60 is moved reversely to its starting position and its lug 68 is re-engaged with the pin 70.

The tack tubes 50 at their delivery ends are supported on arms 80 which are fast on brackets 82 on the frame of the machine and are provided with tack delivery openings to align with the tubes, as shown in Fig. 3, the ends of the arms in which the openings are formed being positioned adjacent to the paths of inward and outward movement of the different respective tacker arms 30 and 32. To receive the tacks from the tubes and to carry them into driving position the tacker arms 30 and 32 are provided with tack carriers 84 mounted on pivots 86 to swing alternately into position under the ends of the tubes and into alignment with the tack drivers. In the construction shown each of the tack carriers is locked in driving or tack presenting position, as indicated in Fig. 3, by means of a pawl or latch 130

88 which is pivoted on the tacker arm and engages a projection 90 on the carrier to hold the latter against an abutment (not shown) on the tacker arm. The pawl 88 is normally held in its operative position by means of a spring plunger 92, the locking means being thus effective during the inward movement of the tacker arms toward the shoe and their outward return movement. When the arms arrive at their outermost position the outer ends of the pawls 88 are carried into engagement with adjustable stop screws 94 whereby they are swung about their pivots to disengage them from the projections 90 and to unlock the tack carriers. At this point, however, the several carriers are subjected to the control of additional mechanism comprising gear segments 96 pivotally mounted on the brackets 82 and connected together by means of lever arms 98 and links 100, these gear segments being arranged to engage cooperating gear segments 102 formed on the outer ends of the different respective tack carriers. The gear segment 96 at the right hand side of the machine is fast on a rock shaft 104 on which is also mounted a larger gear segment 106 in engagement with a co-operating gear segment 108 formed on an upright rock shaft 110 provided with an arm 112 on which is a roll 114 engaging in a cam groove 116 formed in a cam disk 118 on the cam shaft 6. The cam groove 116 is so disposed as to operate the gear segment 108 and its connected mechanism in the first stage of the cycle of operations of the machine to swing the several tack carriers 84 into tack receiving position under the delivery ends of the tack tubes in time to receive the tacks blown through the tubes by the action of the pneumatic means hereinbefore described. The tack carriers are held in this position by the operating mechanism during the pause in the cycle following the pulling of the upper, the tacks thus having time to settle in the carriers before they are moved to driving position. In the second stage of the cycle, before the tacker arms begin their inward swinging movement, reverse movement is imparted to the tack carriers by the action of the cam 116 and its connected mechanism to carry the tacks into driving position, and as the tacker arms begin their inward movement the pawls 88 are released to the action of the spring plungers 92 and immediately become effective to lock the carriers in the manner hereinbefore explained before the gear teeth are disengaged. It will be understood that in Fig. 3 a point in the cycle is indicated wherein the tacker arms are in an intermediate position in the course of their outward return movement after the operations on a shoe have been completed.

The construction of the tack carriers is illustrated more in detail in Figs. 4, 5 and 6 which show one of the two carriers that operate at opposite sides of the shoe. It will be seen that the carrier is provided with tack pockets 120 for alinement with the delivery tubes and with the tack drivers in the different respective positions of the carrier, the lower ends of these pockets being normally closed by oppositely movable plates 122 and 124 which are normally pressed together by a spring 126 and are forced apart in opposite directions by the tack drivers in the operative movement of the drivers. Mounted on each of the tacker arms 30 and 32 to extend over and close the upper ends of the tack pockets 120 when the carriers are in driving position are oppositely movable plates 128 and 130 similar to the plates 122 and 124 and similarly controlled by a spring 132 to permit them to be forced apart in opposite directions by the pressure of the tacks and of the tack drivers.

For imparting operative movement to the cam shaft 6 the machine is provided with a horizontal driving shaft 134 mounted in bearings in the base 136 of the machine and extending rearwardly from the cam disc 118, this disc being provided with a beveled gear 138 for engagement with a beveled pinion 140 on the shaft 134. On its rear end the shaft 134 carries a belt driven pulley 142 mounted to turn idly on the shaft except when connected thereto by clutch mechanism. Keyed to the shaft 134 to rotate therewith and to slide lengthwise thereon is a clutch member 144 to which is fastened a ring 146 having on its rear side an external cone face adapted to engage an internal cone face formed on a co-operating clutch ring 148 on the pulley 142. The ring 146 has on its front side a flange 150 arranged to engage a co-operating brake flange on a stationary bracket member 152 which is fast on the base. To force the clutch member 144 into engagement with the member 148 the machine is provided with springs 154 which tend to force the member 144 toward the left (Fig. 1).

For controlling the clutch, the member 144 is provided with an annular groove 156 in which is a ring 158 having trunnions extending into the arms of a forked lever 160 which is pivoted at its upper end on the member 152 and is connected by a rod 162 to controlling mechanism at the front of the machine. Fast on the front end of the rod 162 is a controlling member 164 which is yieldingly upheld by a spring plunger 166. On the upper face of the member 164 is a block 168 arranged to be engaged by a block 170 on the lower end of a brake lever 172. The lever 172 is pivoted on a bracket 174 and is provided at its upper end with a ball projection to engage in a

cam groove 176 in the cam disk 118. Normally the lever 172 through the action of its cam presses the member 164 and the rod 162 toward the right (Fig. 1) to disconnect 5 the parts of the clutch and apply the brake. For starting the machine, the controlling member 164 is arranged to be pulled downwardly by a link 178 which passes through a slot in the member 164 and carries a wear 10 plate 180 to hook over the end of the block 168, this link being connected at its lower end to a treadle 182 normally upheld against an adjustable stop screw 184 by means of a spring 186. Upon such depression of the 15 member 164 its block 168 is released from the block 170 on the brake lever and the springs 154 are then permitted to act to release the brake and to set the clutch and start the machine. As the member 164 is thus 20 moved toward the left (Fig. 1) its block 168 is carried out of engagement with the wear plate 180 on the link 178, whereupon the spring plunger 166 acts to force the member 164 upwardly as far as permitted 25 by the block 170 on the brake lever. It will be understood that by the action of the cam 176 the brake lever 172 is moved into position to engage the end face of the block 168 and then to impart a return movement 30 toward the right to the member 164 for releasing the clutch and applying the brake at the end of each stage of the cycle of operations of the machine. If at the time of 35 such return movement of the controlling member 164 the treadle 182 has not been released to permit its link 178 to rise into position for operative connection with the controlling member, the link is pushed back by the member 164 against a spring plunger 188 40 which serves to swing the link into position for its wear plate 180 to project over the plate 168 when the treadle is eventually released. In consequence of this arrangement the treadle must be fully raised before the 45 clutch can again be tripped.

The machine is also provided with mechanism for controlling the clutch and the brake to permit the operator, if he so desires, to release the brake without setting the 50 clutch. For this purpose there is pivotally mounted on the base of the machine a lever 190 having a projecting lug 192 to be moved, for example by the operator's foot, into or out of the path of movement of a lug 194 on the 55 front end portion of the controlling member 164. These lugs are so arranged as to permit the controlling member, upon depression of the treadle, to be moved far enough by the springs 154 to release the brake but not 60 far enough to carry the clutch member 146 into engagement with the member 148. The member 190 may thus serve as a safety device to prevent starting of the machine at 65 undesired times and is also useful when it is desired to turn the machine over by hand.

To facilitate such manual movement of the operating parts of the machine, a hand wheel 196 is provided, this wheel being mounted on the end of a horizontal shaft 198 on the inner end of which is a beveled gear 200 meshing with the gear 138. The hand wheel 196 is thus mounted at the side of the machine in position to be engaged and turned conveniently by the operator as he stands in his usual working position, thus 70 enabling him as he turns the machine through its cycle to view the different operating instrumentalities from substantially the same position which he occupies in the normal operation of the machine. 75

In the construction shown the substantially upright cam shaft 6 together with the shoe positioning means and the upper pulling and the overlaying and fastening mechanisms are mounted upon a supporting head 202 which is mounted on a horizontal pivot 204 on the base 136 to permit it to swing from the normal position indicated in Fig. 1 to the position indicated 80 in Fig. 2. The head 202 is normally supported at its rear by means of lugs 206 which project from the column 41 and are engaged by a bracket 208 which forms a part of the head 202. The head 202 is secured normally in the position indicated 85 in Fig. 1 by means of detachable tie plates 210. Upon disconnecting these tie plates, detaching the rod 48 from the bell-crank 46, and disconnecting the tack tubes, the head of the machine may be turned to the 90 position indicated in Fig. 2. In this position a strut 212 which is pivoted on the head rests upon the floor and supports the weight of the head. The operator is thus afforded a better access to the interior of 95 the machine by reason of the fact that the cam shaft is in a horizontal position and more fully exposed, and is also afforded better access to parts which are normally 100 enclosed substantially within the base in 105 order to exclude tacks and dirt. This arrangement is particularly convenient in 110 making adjustments or repairs or in replacing parts of the mechanism. It will be observed that when the head is swung 115 from the position of Fig. 1 to that of Fig. 2 the gear 138 is disconnected from the pinion 140 and that the brake lever 172 is also 120 swung out of operative relation to the controlling member 164, and since the hand 125 wheel 196 remains operatively connected to the cam shaft and swings with the head, the operator is enabled to turn the machine over by hand if he so desires when the head is 130 swung to its inoperative position. Before swinging the head over the operator preferably moves the control lever 190 into position to prevent actuation of the clutch when the member 164 is released by the brake lever 172.

Having described the invention, what we claim as new and desire to secure by Letters Patent of the United States is:

1. In a machine of the class described, the combination with means for working an upper over a last, of means for fastening the upper comprising a fastener carrier mounted for movement from retracted position toward fastener inserting position and for additional fastener transferring movement, and mechanism for imparting to said carrier its fastener transferring movement prior to its movement toward fastener inserting position.
2. In a machine of the class described, the combination with means for working an upper over a last, of means for fastening the upper comprising a fastener carrier mounted for movement from an initial retracted position toward fastener inserting position and for additional fastener transferring movement, and mechanism for imparting to said carrier its fastener transferring movement comprising connections arranged to be broken by the movement of the carrier toward fastener inserting position.
3. In a machine of the class described, the combination with means for working an upper over a last, of means for fastening the upper comprising a fastener carrier mounted for movement from an initial retracted position toward fastener inserting position and for additional fastener transferring movement, mechanism for imparting to said carrier its fastener transferring movement comprising connections arranged to be broken by the movement of the carrier toward fastener inserting position, and a device automatically operative to lock the carrier when said connections are broken.
4. In a machine of the class described, the combination with means for working an upper over a last, of means for fastening the upper comprising a fastener inserting device movable from an initial retracted position toward fastener inserting position prior to its fastener inserting movement, a fastener carrier mounted for movement with the fastener inserting device between said different positions and also for movement in a different direction and relatively to said device from a fastener receiving position into position to present a fastener for the inserting operation, and mechanism for imparting to said carrier its fastener presenting movement while the fastener inserting device is in its retracted position.
5. In a machine of the class described, the combination with means for working an upper over a last, of means for fastening the upper comprising a fastener inserting device movable from an initial retracted position toward fastener inserting position prior to its fastener inserting movement, a fastener carrier mounted for movement with the fastener inserting device between said different positions and also for movement in a different direction and relatively to said device from a fastener receiving position into position to present a fastener for the inserting operation, and mechanism for imparting to said carrier its fastener presenting movement while the fastener inserting device is in its retracted position.
6. In a machine of the class described, the combination with means for working an upper over a last, of means for fastening the upper comprising a tacker arm mounted for movement toward and from the shoe and provided with a tack driver, a tack carrier mounted on said arm for movement between a tack receiving position and a position for presenting a tack in operative relation to said driver, and mechanism automatically operative while said tacker arm is in its retracted position away from the shoe to move said carrier into tack receiving position and subsequently into tack presenting position.
7. In a machine of the class described, the combination with means for working an upper over a last, of means for fastening the upper comprising a tacker arm mounted for movement toward and from the shoe and provided with a tack driver, means for delivering a tack adjacent to the path of movement of said arm, a tack carrier mounted on said arm for movement in opposite directions alternately into position to receive a tack as thus delivered and into position to present the tack in alignment with the driver, and mechanism automatically operative independently of said movement of the tacker arm to move the tack carrier in said different directions.
8. In a machine of the class described, the combination with means for working an upper over a last, of means for fastening the upper comprising a fastener inserting device movable from an initial retracted position toward fastener inserting position prior to its fastener inserting movement, mechanism for moving said device toward fastener inserting position, a fastener carrier mounted for movement with the fastener inserting device between said different positions and also for movement relatively to said device from a fastener receiving position into position to present a fastener for the inserting operation, and additional mechanism automatically operative independently of the movement of the fastener inserting device for imparting to said carrier its fastener presenting movement.
9. In a machine of the class described, the combination with means for working an upper over a last, of means for fastening the upper comprising a fastener inserting device

- movable from initial retracted position toward fastener inserting position prior to its fastener inserting movement, a fastener carrier mounted for movement with the fastener inserting device between said different positions and also for movement relatively to said device from a fastener receiving position into position to present a fastener for the inserting operation, and mechanism for imparting to said carrier its fastener presenting movement comprising connections arranged to be broken by the movement of the fastener inserting device toward fastener inserting position.
- 10 15. 10. In a machine of the class described, the combination with means for working an upper over a last, of means for fastening the upper comprising a fastener inserting device movable from initial retracted position toward fastener inserting position prior to its fastener inserting movement, a fastener carrier mounted for movement with the fastener inserting device between said different positions and also for movement relatively to said device from a fastener receiving position into position to present a fastener for the inserting operation, mechanism for imparting to said carrier its fastener presenting movement comprising connections arranged to be broken by the movement of the fastener inserting device toward fastener inserting position, and additional mechanism for locking said carrier in its fastener presenting position when said connections are broken.
- 20 25 30 35 40 45 50 55 60 65 70 75 80 85 90 95 100 105 110 115 120 125 130
11. In a machine of the class described, the combination with means for working an upper over a last, of means for fastening the upper comprising a fastener driver mounted for movement toward and from driving position independently of its driving movement, a fastener carrier mounted for movement toward and from driving position with said driver and for additional movement relatively to the driver between a fastener receiving position and a position for presenting a fastener to the driver, and mechanism for moving said carrier into fastener receiving position and fastener presenting position alternately comprising parts arranged to be disconnected upon movement of the driver toward driving position and to be connected again upon return movement of the driver.
12. In a machine of the class described, the combination with means for working an upper over a last, of means for fastening the upper comprising a tacker arm mounted for movement toward and from the shoe and provided with a tack driver, a tack carrier mounted on said arm for movements alternately into position to receive a tack and into position to present a tack to the driver, mechanism for imparting to said carrier its different movements while the tacker arm is in its retracted position away from the shoe comprising gears arranged to be disconnected upon movement of the arm toward the shoe, and a locking device automatically operative to lock the carrier in tack presenting position upon movement of the arm toward the shoe and to unlock the carrier upon return movement of the arm.
13. In a machine of the class described, the combination with means for working an upper over a last, of means for fastening the upper comprising a fastener inserting device mounted for positioning movement toward and from the shoe independently of its fastener inserting movement, a fastener carrier movable toward and from the shoe with said fastener inserting device and also movable relatively to said device in opposite directions alternately to receive a fastener and to present the fastener for the inserting operation, means for imparting operative movement to said carrier, and mechanism automatically operative upon movement of the fastener inserting device toward the shoe to lock said carrier in fastener presenting position and upon return movement of said device to unlock the carrier.
14. In a machine of the class described, the combination with means for working an upper over a last, of means for fastening the upper comprising a fastener inserting device mounted for positioning movement toward and from the shoe independently of its fastener inserting movement, a fastener carrier mounted for movement toward and from the shoe with said fastener inserting device and for additional movement relatively to said device between a fastener receiving position and a position for presenting a fastener for the inserting operation, means for moving said carrier between its receiving and presenting positions, a pawl for locking the carrier in fastener presenting position, and means for controlling said pawl to lock and to unlock the carrier respectively upon movements of the fastener inserting device toward and from the shoe.
15. In a machine of the class described, the combination with means for working an upper over a last, of means for fastening the upper comprising a tacker arm mounted for movement toward and from the shoe and provided with a tack driver, a tack carrier mounted on said arm for movements alternately into position to receive a tack and into position to present a tack to the driver, mechanism for imparting to said carrier its different movements while the tacker arm is in its retracted position away from the shoe comprising gears arranged to be disconnected upon movement of the arm toward the shoe, and a locking device automatically operative to lock the carrier in tack presenting position upon movement of the arm toward the shoe and to unlock the carrier upon return movement of the arm.
16. In a machine of the class described, the combination with means for working an upper over a last positioned bottom downward, of means for fastening the upper com-

- prising a fastener inserting device mounted for movement from initial retracted position into position under the bottom of the shoe for driving a fastener upwardly into the shoe, means for delivering a fastener point upward at one side of the path of movement of said device, a carrier mounted for movement with said fastener inserting device and also for movement relatively to said device to transfer a fastener from said delivery means and present it for the driving operation, mechanism automatically operative while said fastener inserting device is in its retracted position to impart fastener transferring movement to said carrier, and additional mechanism for holding the carrier in fastener presenting position. 10
17. In a machine of the class described, the combination with means for pulling an upper over a last, of means for fastening the upper comprising fastener inserting devices mounted for movements respectively lengthwise and laterally of the shoe into and out of fastener inserting positions at the toe 25 end and at opposite sides of the shoe, each of said devices being provided with a fastener carrier movable relatively thereto from a fastener receiving position to fastener presenting position, and mechanism 30 for imparting fastener presenting movements to said carriers while fastener inserting devices are in their initial retracted positions away from the shoe. 18. In a machine of the class described, the combination with means for pulling an upper over a last, of means for fastening the upper comprising fastener inserting devices mounted for movements respectively lengthwise and laterally of the shoe into and 40 out of fastener inserting positions at the toe end and at opposite sides of the shoe, each of said devices being provided with a fastener carrier movable relatively thereto from a fastener receiving position to fastener presenting position, and mechanism automatically 45 operative while said fastener inserting devices are in their initial retracted positions away from the shoe to move said carriers into fastener receiving position and subsequently into fastener presenting position. 50
19. In a machine of the class described, the combination with means for pulling an upper over a last, of means for fastening the upper comprising fastener inserting devices 55 mounted for movements respectively lengthwise and laterally of the shoe into and out of fastener inserting positions at the toe end and at opposite sides of the shoe, each of said devices being provided with a fastener carrier movable relatively thereto from a fastener receiving position to fastener presenting position, mechanism automatically operative while said fastener inserting devices are 60 in their initial retracted positions away from the shoe to impart fastener presenting movements to said carriers, and additional mechanism for locking said carriers in fastener presenting position as the fastener inserting devices move toward fastener inserting position. 65
20. In a machine of the class described, the combination with means for pulling an upper over a last, of means for fastening the upper comprising tacker arms mounted for movements respectively lengthwise and laterally of the shoe into and out of position for fastening the upper at the toe end and at opposite sides of the shoe, tack carriers mounted on said tacker arms for movements relatively to said arms alternately into tack receiving position and into position to present the tacks for the tack driving operation, each of said carriers being provided with gear teeth, co-operating gears arranged to engage the gear teeth of the different respective carriers when the tacker arms are in their retracted positions away from the shoe, and mechanism for operating said different gears simultaneously to impart tack transferring movements to said carriers. 75
21. In a machine of the class described, the combination with upper pulling means constructed to pull an upper in one stage of the cycle of the machine and to come automatically to rest with the upper held under tension, of means operative in a different stage of the cycle upon a subsequent starting of the machine to fasten the upper, said fastening means comprising a fastener inserting device mounted for movement from initial retracted position toward fastener inserting position prior to its fastener inserting movement, a fastener carrier mounted for movement with said fastener inserting device between said different positions and also for movement relatively to said device between a fastener receiving position and a fastener presenting position, and operating mechanism for moving said carrier into fastener receiving position in the upper pulling stage of the cycle and into fastener presenting position in the upper fastening stage of the cycle. 80
22. In a machine of the class described, the combination with upper pulling means constructed to pull an upper in one stage of the cycle of the machine and to come automatically to rest with the upper held under tension, of means operative in a different stage of the cycle upon a subsequent starting of the machine to fasten the upper, said fastening means comprising a fastener inserting device mounted for movement from an initial retracted position toward fastener inserting position prior to its fastener inserting movement, means for delivering a fastener adjacent to the path of movement of said device in the upper pulling stage of the cycle, a fastener carrier arranged to receive 100

a fastener thus delivered and mounted for movement relatively to said fastener inserting device to transfer the fastener, and operating mechanism for imparting such transferring movement to the carrier in the upper fastening stage of the cycle prior to movement of the fastener inserting device toward fastener inserting position.

23. In a machine of the class described,

10 the combination with upper pulling means constructed to pull an upper over a last in one stage of the cycle of the machine and to come automatically to rest with the upper held under tension, of fastening means operative in a different stage of the cycle upon a subsequent starting of the machine to drive upper securing fasteners, and pneumatic means automatically operative in the upper pulling stage of the cycle to deliver fasteners 20 to said fastening means.

24. In a machine of the class described, the combination with upper pulling means constructed and arranged to pull an upper over a last positioned bottom downward in

25 one stage of the cycle of the machine and to come automatically to rest with the upper held under tension, of fastening means operative in a different stage of the cycle upon a subsequent starting of the machine to drive upper securing fasteners upwardly into the bottom of the shoe, means for delivering fasteners to said fastening means comprising conduits curved to effect an inversion of the fasteners and to deliver them point upward, and pneumatic means operative in the upper pulling stage of the cycle to deliver a blast 30 of air for forcing fasteners through said conduits.

25. In a machine of the class described, 40 the combination with upper pulling means constructed and arranged to pull an upper over a last positioned bottom downward in one stage of the cycle of the machine and to come automatically to rest with the upper held under tension, of fastening means operative in a different stage of the cycle upon a subsequent starting of the machine to drive upper securing fasteners upwardly into the bottom of the shoe, means for delivering 45 fasteners to said fastening means comprising conduits curved to effect an inversion of the fasteners and to deliver them point upward, an air pump for delivering a blast of air into said conduits to force fasteners through the conduits, and mechanism for operating said air pump in the upper pulling stage of the cycle of the machine.

26. In a machine of the class described, 50 the combination with means for pulling an upper over a last positioned bottom downward, and means for driving fasteners upwardly into the shoe, of fastener supplying means comprising a separator, a driving shaft, connections operated by said shaft for imparting operative movement to said sepa-

rator, and means for effecting pneumatically the transfer of fasteners from said separator and inversion of the fasteners to present them point upward to the upper fastening means comprising an air pump and connections between the pump and said separator operating connections to operate the pump in time relation to the separator.

27. In an upper pulling machine, the combination with means for pulling an upper and means for fastening the upper, of means for delivering a fastener pneumatically to said fastening means comprising an air cylinder, a piston in said cylinder, a spring for operating the piston to deliver 75 a blast of air, a piston rod connected to said piston to move it against the resistance of said spring, and mechanism automatically operative in such movement of the piston rod to disconnect it from the piston and release the piston to the action of the spring.

28. In an upper pulling machine, the combination with means for pulling an upper and means for fastening the upper, of a separator for fasteners, and means for transferring fasteners pneumatically from said separator to the fastening means comprising an air cylinder, a piston in said cylinder, a spring for forcing the piston into the cylinder to deliver a blast of air, a piston rod for imparting to said piston its suction stroke against the resistance of said spring, means for operating said piston rod in time relation to the separator, and a device automatically operative to disconnect the piston rod from the piston at a predetermined point in the suction stroke of the piston.

29. In a machine of the class described, the combination with means for pulling an upper over a last and means for fastening the upper, of mechanism for imparting operative movements to said upper pulling and upper fastening means comprising connected shafts disposed in angular relation 105 to each other, clutch and brake mechanism associated with one of said shafts, and means for controlling said clutch and brake mechanism from the other shaft.

30. In a machine of the class described, 115 the combination with means for pulling an upper over a last and means for fastening the upper, of mechanism for imparting operative movements to said upper pulling and upper fastening means comprising an upwardly extending cam shaft and a substantially horizontal driving shaft geared to said cam shaft, clutch and brake mechanism associated with said driving shaft, and controlling means for said clutch and brake mechanism arranged to be operated by said cam shaft.

31. In a machine of the class described, 125 the combination with means for pulling an upper over a last and means for fastening 130

the upper, of mechanism for imparting operative movements to said upper pulling and upper fastening means comprising an upwardly extending cam shaft, a driving shaft extending substantially horizontally and geared at its inner end to said cam shaft, controlling mechanism for starting and stopping the machine comprising a clutch and a brake positioned at the outer end of 5 said driving shaft, and connections controlled by the cam shaft for disconnecting the clutch and applying the brake.

32. In a machine of the class described, the combination with means for pulling an 10 upper over a last positioned bottom downward, and means for driving fasteners upwardly into the shoe, of mechanism for imparting operative movements to said upper pulling and fastener driving means comprising 15 a cam shaft extending upwardly substantially under the shoe, a driving shaft geared to said cam shaft and extending substantially horizontally, and clutch and brake mechanism associated with said driving 20 shaft and controlled by the cam shaft for bringing the machine automatically to a 25 stop.

33. In a machine of the class described, the combination with means for pulling an 30 upper over a last positioned bottom downward, and means for driving fasteners upwardly into the shoe, of mechanism for imparting operative movements to said upper pulling and fastener driving means comprising 35 a cam shaft extending upwardly substantially under the shoe and a driving shaft connected to said cam shaft and extending rearwardly in a substantially horizontal direction, a clutch and a brake at the 40 rear end of said driving shaft, and mechanism operated by said cam shaft for releasing the clutch and applying the brake at a determinate time in the cycle of operations.

34. In a machine of the class described, 45 the combination with means for pulling an upper over a last, and means for fastening the upper, of mechanism for imparting operative movements to said upper pulling and upper fastening means comprising a cam 50 shaft and a driving shaft connected together and disposed in angular relation to each other, a clutch and a brake associated with said driving shaft, a controlling member movable in one direction to release the brake 55 and set the clutch and in the opposite direction to release the clutch and apply the brake, a spring for imparting said first named movement to the controlling member, a device operated by said cam shaft to 60 impart movement in the opposite direction to said member to stop the machine, and manual means for disconnecting the controlling member from said device to release it to the action of the spring and start the 65 machine.

35. In a machine of the class described, the combination with means for pulling an upper over a last and means for fastening the upper, of mechanism for imparting operative movements to said upper pulling and upper fastening means comprising an upwardly extending cam shaft and a substantially horizontal rearwardly extending driving shaft geared to said cam shaft, a clutch and a brake at the rear end of said driving shaft, controlling mechanism comprising a controlling member extending forwardly from said clutch and brake, a spring for moving said member rearwardly to set the clutch and release the brake, a lever operated by said cam shaft for imparting forward movement to said member to release the clutch and apply the brake, and treadle means for disconnecting the controlling member from said lever to release the member to the action of said spring. 70 75 80 85

36. In a machine of the class described, the combination with means for pulling an upper over a last and means for fastening the upper, of mechanism for imparting operative movements to said upper pulling and upper fastening means comprising a cam shaft and a driving shaft disposed in angular relation to each other, a clutch associated with said driving shaft, a controlling member extending from said clutch, a power operated member for engaging said controlling member and holding it normally in clutch releasing position, and a treadle operated link arranged to hook over 90 95 100 said controlling member and disconnect it from said power operated member for starting the machine.

37. In a machine of the class described, the combination with means for pulling an upper over a last and means for fastening the upper, of mechanism for imparting operative movements to said upper pulling and upper fastening means comprising an upwardly extending cam shaft and a substantially horizontal rearwardly extending driving shaft geared to said cam shaft, a brake and a clutch at the rear end of said driving shaft, controlling mechanism comprising a member extending forwardly from said brake and clutch, a lever normally operative to hold said controlling member in a forward position with the clutch released and the brake applied, a tripping device to disconnect the controlling member from said lever, spring means for forcing said member rearwardly to set the clutch and release the brake, and mechanism for operating said lever subsequently to impart reverse movement to said member to stop 110 115 120 125 the machine.

38. In a machine of the class described, the combination with means for pulling an upper over a last and means for fastening the upper, of mechanism for imparting 130

operative movements to said upper pulling and upper fastening means, clutch and brake mechanism for starting and stopping the machine, manual means for normally controlling said clutch and brake mechanism, and additional controlling mechanism arranged to be manipulated by the operator in his normal working position in front of the machine to enable him to release the 10 brake without setting the clutch.

39. In a machine of the class described, the combination with means for pulling an upper over a last and means for fastening the upper, of mechanism for imparting operative movements to said upper pulling and upper fastening means, clutch and brake mechanism for starting and stopping the machine, controlling mechanism arranged to be tripped manually and operative through movement in one direction first to release the brake and then to set the clutch, and a device arranged to be manipulated by the operator in his normal working position in front of the machine 25 and movable into position to stop said controlling mechanism in brake releasing position and before it has arrived in position to set the clutch.

40. In a machine of the class described, the combination with means for pulling an upper over a last and means for fastening the upper, of mechanism for imparting operative movements to said upper pulling and upper fastening means comprising an upwardly extending cam shaft and a substantially horizontal rearwardly extending driving shaft geared to said cam shaft, a clutch and a brake at the rear end of said driving shaft, controlling mechanism comprising a member extending forwardly from said clutch and brake and arranged to be tripped manually to cause it to move in one direction to release the brake and then to set the clutch, and a device at the front 45 of the machine movable at the will of the operator into position to prevent said member from moving far enough to set the clutch while permitting it to move a sufficient distance to release the brake.

50. 41. In a machine of the class described, the combination with means for pulling an upper over a last and means for fastening the upper, of mechanism for imparting operative movements to said upper pulling and upper fastening means, clutch and brake mechanism for starting and stopping the machine, means enabling the operator to release the brake without setting the clutch, and mechanism arranged to be 55 manipulated by the operator in his normal working position in front of the machine to turn the machine manually through its operating cycle while the brake is thus released.

55. 42. In a machine of the class described,

the combination with means for pulling an upper over a last and means for fastening the upper, of mechanism for imparting operative movements to said upper pulling and upper fastening means, clutch and brake mechanism for starting and stopping the machine, means enabling the operator in his normal working position in front of the machine to release the brake without setting the clutch, and mechanism comprising a 70 hand wheel mounted at one side of the machine to permit the operator to turn the machine through its operating cycle while the brake is thus released.

43. In a machine of the class described, the combination with means for pulling an upper over a last and means for fastening the upper, of power operated mechanism for imparting operative movements to said upper pulling and upper fastening means, and mechanism positioned within reach of the operator in his normal working position to enable him to turn the machine manually through its operating cycle while viewing the parts as he normally does in the power 90 effected operation of the machine.

44. In a machine of the class described, the combination with means for pulling an upper over a last positioned bottom downward and means for fastening the upper, of power driven mechanism for imparting operative movements to said upper pulling and upper fastening means comprising an upwardly extending cam shaft, a driving shaft geared to said cam shaft, and mechanism also geared to said cam shaft and comprising a hand wheel positioned at one side of the machine to enable the operator to turn the machine through its operating cycle.

45. In a machine of the class described, the combination with means for pulling an upper over a last positioned bottom downward and means for fastening the upper, of power driven mechanism for imparting operative movements to said upper pulling and upper fastening means comprising an upwardly extending cam shaft, a substantially horizontal rearwardly extending driving shaft connected to said cam shaft, clutch and brake mechanism associated with said driving shaft, means enabling the operator to release the brake without setting the clutch, and mechanism connected to said cam shaft and comprising a hand wheel mounted at 115 one side of the machine within reach of the operator in his normal working position to permit him to turn the machine through its operating cycle while the brake is thus released.

46. In a shoe machine, the combination with shoe positioning means, devices for operating on the shoe, and a power shaft for imparting operative movements to said devices, of a support for said shoe positioning 130

means, operating devices and power shaft mounted for movement from a normal position into a different position to facilitate adjustments and repairs while the different parts on the support are maintained in normal relation to one another.

47. In a machine of the class described, the combination with last and upper positioning means, and means for pulling over and for fastening the upper, of a support for said different means mounted for movement from normal position into a different position to facilitate adjustments and repairs while the different means are maintained in the same relation to one another.

48. In a machine of the class described, the combination with last and upper positioning means, and means for pulling over and for fastening the upper, of a support for said different means mounted for swinging movement from normal position into a different position to facilitate adjustments and repairs, and a member on said support mounted to swing automatically into position to sustain the parts when the support is swung to said different position.

49. In a machine of the class described, the combination with upper pulling and upper fastening devices, and mechanism comprising a cam shaft for imparting operative movements to said devices, of a support for said upper pulling and upper fastening devices and cam shaft mounted to swing from a normal position to a position in which said cam shaft is presented at a different angle to facilitate adjustments and repairs.

50. In a machine of the class described, the combination with a shoe rest arranged to position a shoe bottom downward, upper pulling and fastening devices, and operating mechanism comprising an upwardly extending cam shaft, of a support for said shoe rest and upper pulling and fastening devices and cam shaft mounted for swinging movement from normal position into position in which the cam shaft is presented substantially horizontally.

51. In a machine of the class described, the combination with upper pulling and fastening devices, and operating mechanism comprising a cam shaft, of a support for said upper pulling and fastening devices and cam shaft mounted for movement to present the parts in an abnormal position for inspection, and means connected to said cam shaft to enable the operator to turn said shaft manually while the parts are in said abnormal position.

52. In a machine of the class described, the combination with upper pulling and fastening devices, and operating mechanism comprising a cam shaft, of a support for said upper pulling and fastening devices and cam shaft mounted for movement to

present the parts in an abnormal position for inspection, and mechanism comprising a hand wheel mounted on said support to enable the operator to turn said cam shaft manually when the parts are either in normal or in abnormal position.

53. In a machine of the class described, the combination with upper pulling and fastening devices, and operating mechanism comprising a cam shaft, of a support for said upper pulling and fastening devices and cam shaft mounted for movement from normal position to present the parts in an abnormal position for inspection, a clutch controlled driving shaft, and a connection between said driving shaft and cam shaft arranged to be broken by movement of said parts to abnormal position.

54. In a machine of the class described, the combination with upper pulling and fastening devices, and operating mechanism comprising an upwardly extending cam shaft, of a support for said upper pulling and fastening devices and cam shaft mounted for swinging movement to present the parts with the cam shaft substantially horizontal, a clutch controlled driving shaft, and a gear connection between said cam shaft and driving shaft arranged to be broken by the movement of said support to its abnormal position.

55. A machine of the class described having, in combination, shoe positioning means, pulling-over means, mechanism for operating said pulling-over means, and a support for said shoe positioning and pulling-over means mounted to swing from normal position into position to disconnect the pulling-over means from its operating mechanism to facilitate adjustments and repairs.

56. A machine of the class described having, in combination, a base, a support mounted on said base for swinging movement from its normal position into position to expose the interior of the machine, shoe positioning means and pulling-over means carried by said support to be swung thereby out of their normal operative position, and power-driven means mounted on said base for operating the pulling-over means.

57. A machine of the class described having, in combination, a base, a support mounted on said base for swinging movement from its normal position, and upper gripping and tacking devices carried by said support to move as a unit from their normal operative position with the support.

58. In a machine of the class described, the combination with a base, of upper pulling means and an operating cam shaft therefore movable as a unit relatively to the base from normal position into a different position to facilitate adjustments and repairs, and means on the base for operating said cam shaft.

59. A machine of the class described having, in combination, pulling-over means movable from normal position into a different position to facilitate adjustments and 5 repairs, and operating mechanism for said pulling-over means comprising parts arranged to be disconnected by movement of the pulling-over means from its normal position and connected again automatically by 10 return of said means to its normal position.

60. A machine of the class described having, in combination, a base, a support mounted on said base for movement from normal 15 position into a position such as to prevent the normal cycle of operations of the machine, and a shoe rest and mechanism for operating on the shoe both carried by said support to move as a unit from their normal operative position with the support.

61. A machine of the class described having, in combination, a base, a support mounted on said base for movement from 20 normal position to a different position, a shoe rest and mechanism for operating on the shoe both carried by said support, and operating means comprising parts mounted 25 respectively on said support and base and arranged to be disconnected by movement of the support from normal position and connected again automatically by return of 30 the support to normal position.

62. In a machine of the class described, the combination with pulling-over means, of a tacker arm movable toward and from 35 the shoe, a tack carrier movable on said arm between tack receiving position and tack presenting position, a latch carried by the arm for holding the carrier in tack present-

ing position, a member operative upon movement of the arm away from the shoe to unlatch the carrier, and means for moving the carrier to receive and present a tack while it is thus unlatched. 40

63. In a machine of the class described, the combination with pulling-over means, of a tacker arm movable toward and from the shoe, a tack carrier movable on said arm between tack receiving position and tack presenting position, means for imparting tack transferring movement to said carrier when 45 the arm is in retracted position away from the shoe comprising intermeshing gear teeth arranged to be disconnected by movement of the arm toward the shoe, a latch carried by the arm for holding the carrier in tack presenting position when said teeth are disconnected, and automatic means for operating said latch to release the carrier after 50 said teeth have been connected by return movement of the arm. 55

64. In a machine of the class described, the combination with pulling-over means, of a tacker arm movable toward and from the shoe, a tack carrier movable on said arm between tack receiving position and tack presenting position, a pawl on the arm for locking the carrier in tack presenting position, and a stop into engagement with which 60 said pawl is carried by movement of the arm away from the shoe for releasing the 65 carrier.

In testimony whereof we have signed our names to this specification.

ARTHUR ERNEST JERRAM.
JOSEPH GOULDBOURN.
